UNITED STATES PATENT OFFICE.

CHARLES A. NELSON, OF UTICA, NEW YORK, ASSIGNOR TO SAVAGE ARMS COMPANY,
OF UTICA, NEW YORK, A CORPORATION OF NEW YORK.

FIREARM.

1,209,872.

Specification of Letters Patent. Patented Dec. 26, 1916.

Application filed April 20, 1915. Serial No. 22,536.

To all whom it may concern:

Be it known that I, CHARLES A. NELSON, a citizen of the United States, residing at Utica, in the county of Oneida and State of 5 New York, have invented certain new and useful Improvements in Firearms, of which the following is a specification.

This invention consists in a novel breech mechanism of the type in which the striker 10 is forced back by camming action as the result of turning the breech-bolt to unlock or release it preliminarily to withdrawing the bolt in opening the gun, and in a novel means for securing together the forearm and 15 barrel of a gun.

In place of holding the striker against turning by adapting it to engage directly with a longitudinal fixed surface (of the receiver) when the striker is cammed back by 20 the breech-bolt in the unlocking rotation thereof, this being the usual construction, I provide a separate or intermediate element, which in effect forms a non-rotating part of the bolt. When the bolt is back, this element 25 is clear of the receiver surfaces which keep it against rotating during the camming, and at that time it is held from turning through the intermediary of the striker, which locks it (against turning) to the 30 breech-bolt, in turn held from turning by a well-known connection with the receiver. When the gun is closed, the striker may be withdrawn by a manual pull directly thereon and turned into such relation thereto as 35 to constitute the "safety" condition of the piece. In this position it effects the locking of the breech-bolt against turning; inasmuch as normally the gun when in "safe" condition is in the otherwise ready-to-fire condition, this locking of the bolt is a notice to the user that there is a cartridge in the chamber and that it only requires to turn the striker out of the safety position to leave the 40 piece ready to be discharged. The pin of the striker is connected with the body part thereof in a novel way facilitating assembling and disassembling, but preventing unintentional disassembling.

The means for securing together the barrel and forearm consists of a band or clip 50 and a retaining pin therefor so formed and associated that each holds the other against working out of place.

In the accompanying drawings, Figure 1 55 is a side elevation of the improved gun,

showing the breech mechanism partly in section, the gun being cocked; Fig. 2 is a longitudinal sectional view, showing the breech-bolt retracted to the full normal limit; Figs. 3 and 4 are a side elevation and an underneath plan of the breech-bolt and striker, showing the latter cammed back by the rotary part of the bolt; Fig. 5 is an underneath plan view of the non-rotary or tail part of the bolt and the striker, showing the latter 60 in the "safe" position. Fig. 6 is a top plan view of the receiver, bolt and striker, the latter being in the cocked position; Fig. 7 is a sectional view on line $y-y$ of Fig. 3, looking forward and showing the receiver tang in 65 section; Fig. 8 is a rear elevation of the rotary part of the bolt; Figs. 9 and 10 are a side and a rear elevation of the body part of the striker; Figs. 11 and 12 are a side and rear elevation of the non-rotary or tail part 70 of the bolt; Fig. 13 shows the assembled tail part of the bolt and the striker removed from the rotary part of the bolt; Fig. 14 is a sectional view on line $x-x$ of Fig. 1; and, Fig. 15 shows a detail of Fig. 14. 75

The gun shown is of the military type. The barrel a is screwed into the receiver b , and the structure including these parts is secured to the stock c by suitable means including the abutment member d (forming 80 the subject of a co-pending application filed by me) and a clip or band e , in itself of well-known type, which is held by its screw f in embracing relation to the forearm, the barrel and the forward reduced end of the 85 barrel cover-piece g (held at its reduced rear end by the abutment member d). A pin h is passed transversely through the forearm so that the rearward half of its diameter, the clip being against the shoulder i of the forearm and cover-piece, is covered by the clip; as for its forward half it protrudes to form the abutments h' which prevent the clip or band e working forward, 90 which in turn holds the pin in place. 95

The forward or rotary part j of the bolt is equipped with a laterally projecting operating arm k which works in the usual L-shaped slot l in the receiver; it is suitably formed in any well-known way at its forward end so that when in the breech-closing position it is locked against rearward movement by the locking shoulder m in the receiver but may be turned to unlock it, and on being then retracted is held against ro- 100 105 110

- tation by the longitudinal ways n of the receiver. At its rear end it has a cam o and near the summit thereof a V-notch p ; also a square-cut notch p' .
- 5 The non-rotary tail part of the bolt is a suitably formed block q having a forwardly projecting externally threaded tubulure r , (whose bore is reduced at the forward end to form the shoulder r'), a forwardly projecting tongue s , a channel t in its forward side concentric with the tubulure, and a downwardly open slot u extending therethrough from front to rear, said slot being widened downwardly from the bore r'' of 70 the tubulure to form the offset slot-portion v , which extends but partway forward, leaving the shoulder w provided with the notch x (Figs. 4, 5 and 7). In its left side the block q is equipped with a rearwardly 75 spring-pressed pin y slightly longer than the front to rear dimension of the block and normally protruding at the back thereof but being capable of being pushed forward until its front end projects at the channel t .
- 10 (Compare Figs. 4 and 5). Lateral underneath guiding surfaces 2 are formed on the block.

The tail-piece is assembled with the forward part of the bolt by screwing its tubulure into the rear end of the latter, which is then received by the channel t (Figs. 3 and 4), the screw-connection affording a swivel joint. When the breech-bolt is in the closed position tongue s by being received in slot l 30 and the tail-piece surfaces 2 by contact with surfaces 3 on the receiver keep the tail-piece from turning on the axis of its swivel connection with the fore part of the bolt.

15 The body part of the striker is a spindle 4 having a milled knob 5 at its rear end and a threaded bore 6 entering its forward end and formed with a vertical fin 7 projecting above and below the spindle, its lower portion having a forward tang 8, beveled at its free end, 40 and on the under side a cocking shoulder 9. The forward or firing pin part 10 of the striker is equipped with a fixed collar 11 and its rear end is threaded.

20 In the assembled relation of the breech-bolt tail-piece, striker and spring, the striker spindle 4 telescopes the tubulure r , the firing-pin is screwed at its rear end into the threaded forward end of the spindle, and the spring 12, penetrated by the firing-pin, 45 is compressed between the forward end of the tubulure and the collar 11. The rearward end of the spring is fitted to a notch r''' (Fig. 12) in the tubulure and its forward end into one of several notches 11' in 50 collar 11. The spring is preferably coiled in the same direction around the axis of the firing pin as the threading of the screw connection between the latter and spindle 6 progresses, and it fits the firing pin rather 60 snugly; therefore when the firing pin is

screwed home and the forward end of the spring is engaged with that notch 11' which necessitates the spring being put under a little tension it is not only kept from turning backward out of the spindle by the yielding resistance of the spring but even if this resistance were forcibly overcome the spring would ultimately be contracted into such tightly wrapped relation to the firing pin that further rotation would be positively prevented.

65 The trigger 13 and sear 14 afford a releasable means to dog the striker of a well-known type. When the trigger is pulled, being pivoted in the sear and having a purchase upon the receiver as shown in Fig. 2, it depresses the (spring-pressed) sear, whose lug 15 is adapted to engage the cocking shoulder 9 of the striker. On backward movement of the breech-bolt, this lug enters 70 the underneath groove 16 in the fore part of the breech-bolt and comes ultimately against the shoulder 17 at its forward end, which marks the normal rearward limit of movement of the bolt; the bolt may be entirely 75 withdrawn from the receiver, by holding down the sear by means of the trigger. The gun shown being of the magazine type, 80 85 is the magazine, 19 the cartridge-platform and 20 the platform spring.

90 Operation: Assuming the parts to be in the positions they occupy immediately after firing, the bolt is locked forward (its arm h being down) and the striker impinges the spent shell, its spindle 4 abutting the shoulder r' of the tubulure r and its fin 7 wholly housed in the slot u of the breech-bolt tail-piece, so that the striker and tail-piece in 95 effect have a spline connection with each other. When the arm h is turned up, cam 100 105 o , by contact with tang 8, cams back the striker until, the arm now being upright, the tang enters the notch p subject to the pressure of spring 12. In thus turning the fore part of the bolt the tail-piece is held 110 from turning in the way already explained. The bolt is now drawn backward and effects the withdrawal and ejection of the empty shell. After the tail-piece clears the receiver 115 it is held from turning by the interlock afforded by the tang 8 being engaged with the notch p . It will be noted that the fin 7 is beveled on the under side at the rear to cam down the sear during backward movement 120 of the bolt. A fresh cartridge having come 125 to position ahead of the bolt, when the latter is now advanced the cocking shoulder 9 of the striker dogs the lug 15 of the sear, leaving the piece cocked as soon as the bolt has reached its forward limit and the arm h 130 has been turned down. To effect the safety condition of the arm, the striker (whose fin 7 now but partly projects into the slot of the tail-piece) may now be withdrawn against the tension of spring 12 until the fin 130

clears the slot and then turned to the lateral limit afforded by the offset portion v of said slot, leaving the tang engaged in the notch x and the upper part of the fin 7 holding the pin y advanced so that its forward end is engaged in the notch p' at the rear of the fore part of the breech-bolt, so that not only are the striker and the firing mechanism thus locked but the breech-bolt locked 10 against rotation. The breech being thus locked closed, the operator is prevented from inadvertent and useless opening thereof through possibly forgetting that the gun is at "safety" and therefore ready to fire when 15 only the striker has been returned into engagement with the sear.

The striker is normally not put at "safety" except when the gun is closed, at which time the tail-piece of the breech-bolt is kept from 20 turning by engagement of its tongue s and surfaces 2 with the receiver, as explained. But in separating the assembled striker, tail-piece and spring from the fore part of the bolt, these parts may be turned as a unit 25 until the threaded swivel connection between the tail-piece and fore part is disestablished if, first, the breech-bolt is sufficiently retracted so that the receiver no longer obstructs rotation of the tail-piece 30 and the striker is retracted until its tang clears notch p , say, by setting the striker in the "safety" position; it being noted that when the fore part of the bolt is turned to unlock it from the receiver notch p' is 35 thrown out of registry with pin y and that the pitch of the screw threading between the tail-piece and fore part is sufficiently steep so that when the former is unscrewed (having set the striker at "safety") the pin y has 40 receded out of contact with the rear end of the fore part before it again registers with and can snap into said notch.

Having thus fully described my invention, what I claim as new and desire to secure 45 by Letters Patent is:—

1. In combination, the receiver, a breech-bolt having two parts one of which is movable relatively to the other into interlocked relation with the receiver, firing mechanism, 50 and firing-mechanism-controlled means movable in said other part to lock said first-named part in the interlocked relation with the receiver.

2. In combination, the receiver, a breech-bolt having two parts one of which is movable relatively to the other into interlocked relation with the receiver, firing mechanism including a striker, and striker-controlled means movable in said other part to lock 55 said first-named part in the interlocked relation with the receiver.

3. In combination, the receiver, a breech-bolt having two parts one of which is rotatable relatively to the other, firing mechanism, and firing-mechanism-controlled means 60

movable in said other part to lock said first-named part against rotation.

4. In combination, the receiver, a breech-bolt having two parts one of which is rotatable and the other held by the receiver 70 against rotation, firing mechanism, and firing-mechanism-controlled means, movable in one of said parts, for interlocking said parts together against relative rotation.

5. In combination, the receiver, a breech-bolt having a part thereof movable into interlocked relation with the receiver, a lockable firing mechanism, and means, controlled by the locked firing mechanism, for locking said part in the interlocked relation with the 75 receiver.

6. In combination, the receiver, a breech-bolt having a part thereof movable into interlocked relation with the receiver, firing mechanism including a lockable striker, and 80 means, controlled by the locked striker, for locking said part in the interlocked relation with the receiver.

7. In combination, the receiver, a breech-bolt having a part thereof rotatable, a lockable firing mechanism, and means, controlled by the locked firing mechanism, for locking said part against rotation. 90

8. In combination, the receiver, a movable breech-bolt, firing mechanism including a 95 striker movable lengthwise of the gun, and striker-controlled means to lock the breech-bolt to the receiver, the striker being rotatable on an axis extending lengthwise of the gun into and out of controlling relation to 100 said means.

9. In combination, the receiver, a breech-bolt having two parts one of which is rotatable relatively to the other, firing mechanism including a striker, and striker-controlled means 105 movable in said other part to lock said first-named breech-bolt part against rotation.

10. In combination, the receiver, a breech-bolt having a part thereof rotatable, firing 110 mechanism including a striker, and striker-controlled means to lock said breech-bolt part against rotation, the striker being rotatable into and out of controlling relation to said means. 115

11. In combination, the receiver, a longitudinally movable breech bolt including a fore part and a tail-part having a swivel connection with each other, said tail-part being rotatable relatively to the fore part in 120 one position of the breech-bolt and held against rotation by the receiver in another position of the breech-bolt, and firing mechanism including a striker having a sliding rotation-preventing contact with the tail part, 125 said striker and the fore part having portions enterable one into the other when the breech-bolt is in the first-named position to lock the tail part to the fore part against rotation. 130

12. In combination, the receiver, a breech-bolt including a fore-part and a tail-part having a disconnetive screw connection with each other, and firing mechanism including a spring-pressed striker normally interlocking said parts against rotation and being longitudinally movable against its spring to clear and thus release one of them and being then revoluble into locked-back relation to the other of them.
13. In combination, a striker including a body part and a firing pin screwed therein, a supporting member affording a rotation-preventing guideway to the body part of the striker, and a spring coiled around the firing pin, said body part and firing pin having means to hold the respective ends of the spring against rotation relatively thereto
14. In combination, a striker including a body part and a firing pin having a screw-connection therewith, a supporting member affording a rotation-preventing guideway to the body part of the striker, and a spring coiled snugly around the firing pin and having its ends respectively engaged with and held against rotation by the firing pin and said member, the spring having its coils progressing around the firing pin axis in the same direction as the threading of said screw-connection.

In testimony whereof I affix my signature.

CHARLES A. NELSON.
